GUIDE FOR HOSE REELS OR THE LIKE

George A. Hannay, Westerlo, N. Y., assignor to Clifford B. Hannay and Son, Inc., Westerlo, N. Y., a corporation of New York

Application April 4, 1955, Serial No. 35,361

Term of patent 14 years

(Cl. D41—1)

Fig. 1.

Fig. 2.

Fig. 1 is a perspective view taken from the top and one side of a guide for hose reels or the like, embodying my new design. The underside of the guide, not shown, is substantially plain.

Fig. 2 is a perspective view taken from the top, front and other side.

The essential features of my design reside in the portions shown in full lines.

I claim:

The ornamental design for a guide for hose reels or the like, substantially as shown and described.
